UNITED STATES PATENT OFFICE.

HUGO R. SLIVINSKI, OF CHICAGO, ILLINOIS, ASSIGNOR TO SHEPARD ELECTRIC CRANE & HOIST CO., OF MONTOUR FALLS, NEW YORK, A CORPORATION OF NEW YORK.

CUPOLA-CHARGING BUCKET.

Application filed January 7, 1922. Serial No. 527,585.

To all whom it may concern:

Be it known that I, HUGO R. SLIVINSKI, a citizen of the United States, residing at Chicago, in the county of Cook and State of Illinois, have invented certain new and useful Improvements in Cupola-Charging Buckets, of which the following is a full, clear, and exact specification.

My invention relates to charging devices, and has particular reference to a bucket adapted for charging cupolas, blast furnaces and the like. Heretofore cupolas have been charged either by hand or by dumping buckets or dump cars full of material through the charging door. The first of these methods is objectionable from a production standpoint because of the high labor cost involved in handling the material (lime, coke, pig iron and scrap) by hand, but results in a more uniform output of the cupola because of the uniform manner in which the materials are charged and spread in the furnace. The second method lowers the cost of the molten iron at the cupola because of the lesser expense involved by charging the materials in large quantities by machinery, but produces an inferior and less uniform iron because the materials when dumped into the cupola in large quantities do not spread evenly but tend to segregate in piles so that instead of having uniform layers of coke and iron descending in the cupola the material descends unevenly, and when the cupola is tapped the iron is at times very hot and fluid and at other times too cold to be poured into molds. By means of my invention the charges are spread in even layers in the cupola fully as well as if done by hand, and the material is handled even more cheaply and with less labor than has heretofore been possible with cupola charging machinery. I am thus able to attain the uniform product heretofore obtainable only by hand charging together with the reduced production cost obtainable only with cupola charging machines.

More specifically, my invention comprises an improved charging bucket which will hold a charge of coke or iron and discharge it into the cupola, spreading the material evenly over the preceding charges.

My invention also comprises an improved charging crane which, in combination with

my improved bucket, is adapted, under control of a single operator, to deliver and spread the charges in a cupola of any size.

Having thus briefly referred to the nature of my invention, reference will now be had to the accompanying drawings for a detailed description of a specific embodiment thereof, the main features of novelty being particularly pointed out thereafter in the claims.

In the drawings—

Fig. 1 is a side elevation partly in section of a preferred form of my improved charging bucket and the ring used when charging coke or other relatively bulky material;

Fig. 2 is a section taken substantially on the line 2—2 of Fig. 1;

Fig. 3 is an enlarged view of a part of Fig. 2, the segments forming the platform of the bucket being omitted;

Fig. 4 is an enlarged sectional view taken substantially on the line 4—4 of Fig. 1;

Fig. 5 is an enlarged vertical section of the plunger housing and head;

Fig. 6 is a side elevation of my improved charging crane and modified form of bucket;

Fig. 7 is an end view of the charging crane showing the two hoisting cables and buffer plate;

Fig. 8 is a side elevation, the lower part being in section, of the modified charging bucket;

Fig. 9 is an enlarged sectional view taken on the line 9—9 of Fig. 8.

Referring now to Figs. 1 to 5, the preferred form of my improved charging bucket has a tubular guide or casing 10 in which a plunger 11 is slidably mounted. The casing has a bell-shaped enlargement 12 at its lower end providing a housing for a plurality of brackets 13 secured by screws 14 to the inner wall of the housing, and having bearings for the pivot pins 15 of the arms 16. The arms are pivotally supported near their inner ends and are provided with segmental gears 17 meshing with a rack 18 formed on the lower end of the plunger 11. The arms extend radially beyond the housing and each is secured to one of a plurality of overlapping segmental plates 19, which, when the arms are in horizontal position as shown in Figs. 1 and 2,

provide a complete circle forming the floor or platform of the charging bucket. The edges of the plates overlap, as shown in Fig. 2, and the arms 16 are preferably secured to one edge since this permits the plates and arms to nest closer together when in dumping position, as shown in dotted lines in Fig. 1, and discharges the material evenly throughout the cupola. However, 10 the arms may be secured to the segments at any desired point. A pair of ears or lugs 20, 21 are formed on opposite sides of the guide 10 near its upper end, and in them is secured the ends of a U-bolt 22 having a ring 23 engaged by the hook 23' to which the lower ends of the hoisting cables 24 are secured. The cables 24 pass over a pair of sheaves on the charging crane and are wound on a drum, as shown in Fig. 6 15 and as will be more fully described later. The plunger 11 is slideable in the guide 10 and has a head 25 secured to its upper end by a screw 26, the head having a pair of buffer cylinders 27, 28 bored to slidably receive the buffers 29, 30 and buffer springs 31, 32 respectively. A transverse bore formed partly in the guide and partly in the plunger provides a bearing for a locking pin or bolt 34, the two ends of which are squared 20 and secured to the forks 35, 36 of a trip arm or lever, the free end of the lever being secured to a trip rope 38. The bolt is cut away centrally at 39 to conform to the curvature of the plunger, and when the trip 25 arm is in the full line position shown in Figs. 1 and 5 the locking pin locks the plunger and guide together, but when the trip lever is raised to dotted line position, the cut-away portion 39 of the bolt comes opposite that portion of the bore in the plunger, which disengages the plunger so that it may slide in the guide, as best shown in Fig. 4. A feather 40 secured to the plunger slides 30 in a slot 41 in the housing, and prevents relative rotation of the parts. A plate 42 (Figs. 1, 6 and 7) is secured to the charging crane between the sheaves over which the hoisting cables run, and is adapted to be engaged by the buffers 29, 30 to close the 35 bucket after its contents have been discharged.

When my charging bucket is being used to deliver coke to the cupola, a ring 43 is supported by chains or cables 44 from the 40 yoke 22 and rests on the platform formed by the segments 19, the height of the ring preferably being sufficient to measure one charge of coke. The diameter of the coke ring and bucket are somewhat less than the 45 diameter of the cupola. For example, I use a bucket 60" in diameter for charging a 68-inch cupola, but an exact ratio between the sizes is not essential. When coke is being charged, the ring 43 is placed on the 50 bucket with the parts as shown in Fig. 1.

The ring is now filled with a charge of coke and the bucket hoisted by means of the cables 24 to the level of the charging door. The crane carrying the bucket is then run forward until the bucket enters the charging door and is centered in the cupola. The operator of the crane then pulls the trip rope 38, which raises the trip lever and releases the plunger 11 for upward movement. The weight of the charge swings the arms 55 16 downward about their pivot points, as shown by dotted lines in Fig. 1, discharging the coke in a uniform layer. As the segments 19 swing downwardly and inwardly the edges *a* which are attached to the arms 16 swing in closer to the center than do the free edges *b*, and when, in final discharge position, the segments are tangent to a cone of which the arms 16 are elements. It will be noted that as the segments swing downwardly and inwardly they have a relative twisting movement about the arms 16, and that as the overlapping edges of adjacent segments separate they discharge a portion of the coke toward the 60 center and impart a whirling motion thereto which assists materially in its even distribution. When the coke has been discharged, the operator of the crane raises the bucket slightly until the buffers 29, 30 strike the 65 plate 42, which forces the plunger 11 downwardly and through the rack 18 and gears 17 raises the arms 16 to horizontal position. When the arms become horizontal, the notch in the plunger comes opposite the latch 34, 70 which permits the trip lever to drop and lock the plunger and housing against relative movement. The bucket is then lowered and is ready to receive another charge of coke. 75

When iron is being charged, the ring 43 is omitted and the iron, which is of relatively small bulk, is piled on the segments 19. It is then spread in the cupola in the same manner as the coke. In practice a plurality of 80 buckets are used, one or more being equipped with rings for charging coke and an equal number without the ring for charging iron, so that while one bucket is being discharged another is being loaded. 85

The bucket shown in Figs. 6 to 9 is the same in general principles of operation as the preferred form just described, but differs somewhat in details of construction. Either type of bucket may be used with the crane 90 45, which is carried by trolleys 46, 47 running on an I-beam 48, the trolley 47 being driven by an electric motor 49 controlled by the operator in the cab 50. The operator occupies a seat 51 conveniently located with respect to a controller 52 for controlling the motor 49, and a similar controller directly 95 back of the first one for controlling the hoisting motor 54 which drives a drum 55 on which the hoisting cables 24 are wound. 100

The beam 56 of the crane extends forwardly beyond the trolley 46 a distance sufficient to reach the center of the cupola, and carries a pair of sheaves 57 over which the hoisting cables run and a sheave 58 for the trip rope which extends rearwardly through the cab 50 to a differential drum 59, which is actuated by a weight 60 to keep the trip rope taut. The hook 23' engages in an eye-bolt 61 10 screwed into the upper end of the plunger 62, which slides in the housing or guide 63, and at its lower end is secured to a head 64 having a ring 65 provided with a plurality of depressions 66 forming fulcrum points or 15 bearings for a plurality of arms 67 secured to or formed integral with segments 68 forming the bottom or platform of the bucket. The arms 67 are pivoted to lugs 69 on the under side of a bell-shaped enlargement 20 70 of the housing, and their inner ends rest on a flange 71 at the lower extremity of the housing. The housing and plunger have a pair of ears or lugs 72, 73 respectively at their upper ends, which are connected by a 25 pair of links 74, 75 forming a toggle joint. A trip lever 76 is fulcrumed on the pivotal connection 77 of the toggle links, and has one end 78 rounded out to bear against the plunger 62 and together with the toggle 30 79 forms a means for locking the plunger and guide against relative movement.

In operation the material to be charged is loaded on the platform formed by the segments 68, the latter being in horizontal position, as shown in full lines in Fig. 8, the 35 toggle and trip lever locking the parts together. It is to be noted that the pivot point 77 in Fig. 8 lies inside of the center line connecting the pivotal connection of the links to the ears 72, 73, and therefore that any 40 force tending to slide the casing upward on the plunger will only force the bearing end of the lever more firmly against the plunger.

Assume now that the bucket has been 45 loaded with a charge, the operator starts the motor 54 and raises the bucket to the level of the cupola charging door. The crane is then run forward until the bucket is centered in the cupola. The operator then reaches 50 upward and pulls the trip rope 38, raising the trip lever 76, which fulcrums about the end 78 bearing against the plunger 62, and moves the center 77 outward beyond the line 55 of centers of the toggle, whereupon the weight of the charge on the arms 67 will cause the latter to tilt about their bearings on the ring 65 and raise their inner ends together with the housing 63. This throws the trip arm and toggle into the dotted line position shown in Fig. 8. The charge slides from 60 the inclined segments 68 and is distributed evenly about the cupola. When the material has been discharged, the bucket is withdrawn from the cupola and lowered to 65 the loading floor, where it receives another

charge. When the bucket is lowered the arms 67 strike on the loading ring or platform 79, which causes them to rock about the ring 65 into horizontal position as the bucket is lowered further, the toggle and trip lever automatically swinging into locking position.

While I have shown the coke ring 43 in combination with but one form of my invention and have shown the other modification in combination with the charging crane, it will of course be understood that the coke ring will be used with either type of bucket when charging coke or other light material, and that each form of bucket is adapted for 80 use with the charging crane.

The drawings and foregoing description are but illustrative of specific forms in which the broad principles underlying my invention may be embodied, and are not to 85 be construed as limiting the invention to a particular construction, but I claim as my invention all modifications and equivalents that may come within the scope of my 90 claims.

What I claim is:

1. In a cupola charging device, the combination of two members one of which is 95 slideable relatively to the other, a collapsible load carrying platform, a lock for preventing collapse of the platform, and means connecting the members and platform permitting movement of the slideable member and collapse of the platform to discharge the load upon release of the lock.

2. In a cupola charging device, the combination of two members slideable relative to one another and normally locked against 100 relative slideable movement, and a collapsible load carrying platform connected to said members, the platform adapted to be collapsed and the load discharged upon unlocking of the members.

3. In a device of the class described, the combination of a plurality of segmental 110 members forming a load carrying platform, a guide to which the segmental members are pivotally connected, a plunger slideable relative to the guide, and means co-operating with the segmental members and plunger 115 whereby relative movement of the plunger and guide will tilt the segmental members about their pivotal connections.

4. In a device of the class described, the combination of a plurality of segmental 120 members forming a load carrying platform, a guide to which the segmental members are pivotally connected, a plunger slideable relative to the guide, means co-operating with the segmental members and plunger permitting relative movement of the plunger and guide and tilting of the segmental members about their pivotal connections, and means for preventing relative movement of the 125 guide and plunger.

5. In a charging bucket, the combination of a casing, a plunger slidable therein, a collapsible load carrying platform surrounding the casing and carried thereby, means 5 connecting the plunger and platform permitting movement of the plunger in the casing and collapse of the platform, and means for locking the plunger against movement when the platform is in horizontal position.

10 6. In a cupola charging device, the combination of a guide, a member slidable in the guide, a plurality of segmental plates pivoted to the guide and forming a charge 15 carrying platform, means co-operating with the plates and slidable member whereby relative movement of the guide and member will tilt the platform to discharge its contents, means for locking the guide and 20 slidable member against relative movement, and means for releasing the locking means to permit relative movement of the guide and member to discharge the contents of the platform.

25 7. In a cupola charging device, the combination of a casing, a plurality of segmental plates pivotally connected to the casing at its lower end and forming a collapsible load carrying platform, a plunger slidable in the casing and having means at the lower end engaging the segmental plates for controlling their movement about their 30 pivotal connections, locking mechanism on the upper ends of the casing and plunger, and means for actuating the locking mechanism to release the plunger whereby the 35 plates will tilt about their pivotal connections.

40 8. In a cupola charging bucket, the combination of a guide having an enlarged housing at its lower end, a plurality of overlapping segments connected to the housing and adapted when in horizontal position to form a charge carrying platform, a plunger slidable within the guide and housing, means on the plunger engaging the segments to normally retain them in horizontal position, means for locking the plunger and guide against relative movement when the segments are in horizontal position, and means for releasing the locking means whereby the segments will tilt to discharge position.

45 9. In a cupola charging bucket, the combination of a guide having an enlarged housing at its lower end, a plurality of overlapping segments connected to the housing and adapted when in horizontal position to form a charge receiving platform, a plunger slid- 50 able within the guide and housing, means on the plunger engaging the segments to normally retain them in horizontal position, means for locking the plunger and guide against relative movement when the segments are in horizontal position, means for

releasing the locking means whereby the segments will tilt to discharge position and means for automatically actuating the locking means when the segments are returned to horizontal position.

55 10. In a cupola charging bucket, the combination of a guide having an enlarged housing at its lower end, a plurality of overlapping segments connected to the housing and adapted when in horizontal position to form a charge receiving platform, a plunger slidable within the guide and housing, means on the plunger engaging the segments to normally retain them in horizontal position, means for locking the plunger and guide against relative movement when the segments are in horizontal position, means for releasing the locking means whereby the segments will tilt to discharge position, means for returning the segments to horizontal position, and means for automatically actuating the locking means when the segments are returned.

60 11. In a cupola charging device, the combination of a casing having a housing at its lower end, a plurality of arms pivoted within the housing, a plurality of segmental plates carried by the arms, a plunger slid- 65 able in the casing and extending into the housing, means on the plunger engaging the inner ends of the arms, means for locking the plunger and casing against relative movement to retain the arms in horizontal position, means for releasing the locking means whereby the plunger will slide in the casing and swing the arms to discharge position, means for returning the plunger in the casing and the arms to horizontal position, and means for automatically actuating the locking means when the arms are thus returned.

70 12. In a cupola charging device, the combination of a casing, a plunger slidable in the casing and having a rack at its lower end, a plurality of arms pivoted to the casing and having segmental gears engaging the rack, a plurality of plates carried by the arms, means for automatically locking the casing and plunger together when the arms are in horizontal position, means for releasing the locking means, and means for returning the plunger to locking position.

75 13. In a cupola charging device, the combination of a relatively stationary member, a member movable axially therein, a collapsible load carrying platform carried by the stationary member, and means connecting the members and platform permitting collapse of the platform and movement of the movable member.

80 14. In a bodily movable cupola charging device, the combination of a relatively stationary guide member, a member movable axially therein, a collapsible platform carried by the guide member, and means in-

- cluding a rack and gear mechanism connecting said members and platform permitting movement of the movable member and collapse of the platform.
- 5 15. In a cupola charging device, the combination of a hollow relatively stationary guide member, a plunger reciprocable therein, means for permitting reciprocation but preventing rotation thereof in the guide member, a collapsible load carrying platform carried by the guide member, and means connecting the guide, plunger and platform, permitting reciprocation of the plunger and collapse of the platform. 70
- 10 16. In a cupola charging device, the combination of a traveling crane having an overhanging beam, a hoisting drum on the crane, a casing carrying a collapsible platform suspended from the overhanging beam and connected by a cable to the drum, a trip arm on the casing controllable from the crane for releasing the collapsible platform, and means on the crane for returning the collapsible platform to charge receiving position 80
- 20 25 when the casing is hoisted to contact said means. 85
17. In a cupola charging device, the combination of a traveling crane having an overhanging beam, a hoisting drum on the crane, a collapsible charging bucket including a relatively movable and a non-movable member, a hoisting cable on the drum and supporting the bucket from the overhanging beam, means for locking the movable member to support the bucket in charge receiving position, and means operable from the crane for releasing the locking means to discharge the contents of the bucket. 90
- 30 35 40 45 50 55 60 65 70 75 80 85 90 95 100 105 110 115 120 125 130
18. In a cupola charging device, the combination of a traveling crane having an overhanging beam, a hoisting drum on the crane, a collapsible charging bucket, a hoisting cable on the drum and supporting the bucket from the overhanging beam, means for locking the bucket in charge receiving position, means operable from the crane for releasing the locking means to discharge the contents of the bucket, and means carried by the crane for returning the bucket to charge receiving position when the bucket is hoisted to contact said means. 100
19. In a cupola charging device, the combination of a traveling crane, a collapsible charging bucket connected to the crane to be raised and lowered thereby, a trip lever on the bucket, means for actuating the trip lever from the crane to discharge the bucket, a buffer on the bucket, and a buffer plate on the crane adapted on contact with the buffer to return the bucket to charge receiving position. 110
20. In a charging bucket, the combination of a central casing having a collapsible bottom, a slidible member controlling the collapsible bottom, locking means co-operating with the slidible member and casing to hold the bottom closed, means for releasing the locking means, a buffer on the slidible member, and means cooperating with the buffer to slide the member in the casing and close the bottom. 120
21. In a cupola charging device, the combination of a pivotally supported tiltable platform adapted to hold a charge, means to lock the platform to prevent tilting, means 75 for inserting the platform into a cupola, and means for releasing the locking means to permit tilting of the platform to discharge its contents into the cupola. 125
22. In a cupola charging device, a bucket having a collapsible circular horizontal bottom adapted to hold a charge, means for inserting the bucket in a cupola, means for collapsing the bottom to discharge and spread the charge, and means on the inserting means adapted to be contacted by the bucket for returning its bottom to horizontal position. 130
23. In a cupola charging device, the combination of a supporting member, a bucket 90 having a circular bottom comprising a plurality of segmental sections pivotally connected at their apices to the supporting member, means for locking the sections in a horizontal position to form a charge holding platform, and means for releasing the locking means to collapse the bottom and release the charge. 135
24. In a cupola charging device, the combination of a supporting member, a bucket 100 having a circular bottom comprising a plurality of overlapping segmental sections pivotally connected at their apices to the supporting member, means for locking the sections in overlapping position in a horizontal plane to form a charge holding platform, and means for releasing the locking means to collapse the bottom and release the charge. 140
25. A bucket for cupola charging devices comprising a supporting member, and a circular bottom made up of a plurality of segmental portions pivotally connected at their apices to the supporting member. 145
26. A bucket for cupola charging devices comprising a supporting member, and a circular bottom made up of a plurality of overlapping segmental portions pivotally connected at their apices to the supporting member. 150
27. A bucket for cupola charging comprising a load carrying platform made up of a plurality of sections, and means for collapsing the sections with a whirling action whereby the load discharged by the platform is evenly distributed. 155
28. A bucket for cupola charging comprising a circular load carrying platform made up of a plurality of segmental sections, and means for collapsing the sections 160

with a whirling action whereby the load discharged by the platform is evenly distributed.

29. A bucket for cupola charging comprising a supporting member, a circular load carrying platform made up of a plurality of segmental sections pivotally connected at their apices to the supporting member, and means for collapsing the sections with a whirling action whereby the load is evenly distributed when discharged.

30. A bucket for cupola charging comprising a supporting member, a circular load carrying platform made up of a plurality of segmental sections pivotally connected at their apices to the supporting member, and arranged in overlapping relation, and means for collapsing the sections with a whirling action whereby the load is evenly distributed when discharged.

31. In a furnace charging device, a central support comprising two members relatively movable in a vertical direction, provisions for suspending said support connected to one of said members, a plurality of load supporting lever arms each fulcrumed on one of said members and engaged by the other member in one relative position of the two members to thereby hold said arms each in an outwardly extending load receiving position but tending to swing down under the action of gravity into a load discharging position when relative movement of the two members is permitted, and means for releasably locking the two members in said one relative position.

In testimony whereof I affix my signature.

HUGO R. SLIVINSKI.
